DESIGN FOR AN ICE BUCKET

Manuel S. Ziskin, University Heights, Ohio, assignor to Kromex Corporation, Cleveland, Ohio, a corporation of Ohio

Application October 9, 1946, Serial No. 133,838

Term of patent 14 years

(Cl. D44—21)

To all whom it may concern:

Be it known that I, Manuel S. Ziskin, a citizen of the United States, residing at University Heights, county of Cuyahoga, and State of Ohio, have invented a new, original, and ornamental Design for Ice Bucket, of which the following is a specification, reference being had to the accompanying drawing, forming a part thereof.

Fig. 1 is a front elevational view of an ice bucket, showing my new design;

Fig. 2 is a top plan view of the ice bucket;

Fig. 3 is a bottom plan view of the ice bucket.

I claim:

The ornamental design for an ice bucket, substantially as shown.

MANUEL S. ZISKIN.
